Patented Aug. 9, 1955

175,323

ELECTRIC DESALTER

Ralph L. Stephenson, Berkeley, Calif.

Application April 12, 1954, Serial No. 29,965

Term of patent 14 years

(Cl. D16—2)

Fig. 1.

Fig. 3.

Fig. 2.

Figure 1 is a perspective view of an electric desalter showing my new design;

Figure 2 is a top plan view of the same; and

Figure 3 is a side view of my electric desalter.

The sides not shown are plain.

I claim:

The ornamental design for an electric desalter, substantially as shown and described.
